UNITED STATES PATENT OFFICE.

WILLIAM FORDYCE BEECHER, OF CLEVELAND, OHIO.

BOILER-FURNACE.

SPECIFICATION forming part of Letters Patent No. 665,165, dated January 1, 1901.

Application filed February 20, 1900. Serial No. 5,914. (No model.)

To all whom it may concern:

Be it known that I, WILLIAM FORDYCE BEECHER, a citizen of the United States, and a resident of Cleveland, in the county of Cuyahoga and State of Ohio, have invented a new and Improved Boiler-Furnace, of which the following is a full, clear, and exact description.

My invention relates to boiler-furnaces, and has for its object to provide a simple and efficient arrangement for securing a complete utilization of the fuel. To this end I construct the furnace as will be fully described hereinafter and particularly pointed out in the claim.

Reference is to be had to the accompanying drawings, forming a part of this specification, in which similar characters of reference indicate corresponding parts in all the views.

Figure 1 is a longitudinal section on line 1 1 of Fig. 2. Figs. 2 and 3 are cross-sections on lines 2 2 and 3 3, respectively, of Fig. 1. Fig. 4 is a sectional plan on line 4 4 of Fig. 1, and Fig. 5 is a longitudinal section on line 5 5 of Fig. 2.

As illustrated in the drawings, the furnace comprises a setting A, having a bridge-wall A' extending transversely in the rear of the grate B. This bridge-wall has in its top a slot A², extending from one side of the furnace to the other and communicating by vertical channels A⁷ with chambers A³, located within the bridge-wall.

Above the throat C, which is located between the grate B and the combustion-chamber D, is arranged a wall A⁴, provided with a slot A⁵, corresponding in location to the slot A² and communicating with chambers A⁶, similar to the chambers A³. The slots A² A⁵ are preferably located in the same vertical plane.

Within the throat C, extending transversely along the top of the bridge-wall A' and the bottom of the upper wall A⁴, are disposed tubes E at each side of the slots A² A⁵, so that the communication of the throat C with said slots is not interfered with by the tubes E. These tubes are connected at their ends by elbows E' with superimposed longitudinal tubes or heads F F', located at each side of the setting. The heads F F' of the same side are connected by a tube G. The upper heads

F are connected by pipes H H' with the boiler I, the pipes leading into the boiler at different levels on opposite sides thereof, as shown in Fig. 2. With one of the lower heads F' is connected a blow-off pipe J, Figs. 4 and 5, having a valve K, and, if desired, this arrangement may be duplicated on the other side of the furnace. This pipe is used for the purpose of removing any sediment or for withdrawing the water from the boiler when not in use.

The chambers A³ A⁶ extend to the outer surface of the setting, as shown in Fig. 2, and are therefore in communication with the surrounding air. The elbows E', heads F F', tubes G, and the major portion of the pipes H H' are embedded in the boiler-setting.

At the rear end of the combustion-chamber the setting has a depending wall or deflector A⁸ to compel the combustion-gases to pass downward and then upward in the uptake A⁹ to enter the boiler-flues. At the front end of the boiler is the smoke-stack L.

In operation the gases rising from the fuel burning on the grate B will pass rearward over the throat C, where they will mingle with air issuing from the transverse slots A² A⁵. In this manner perfect combustion will be insured in the chamber D and the smoke will be consumed. The air supplied through the slots A² A⁵ has become heated during its passage through the chambers A³ A⁶ and channels A⁷ and is therefore in the proper condition to secure highly efficient combustion.

At the same time as the tubes E are fully exposed to the gases and not embedded in the setting such tubes and the water therein can absorb a considerable amount of heat. The connection of the tubes E with the heads F F' by means of elbows E' allows for unequal expansion of the tubes. It will be seen that the tubes E form, as it were, a lining for the horizontal surfaces of the walls A' A⁴, protecting them in a measure against the high heat of the combustion-gases, and, furthermore, these tubes serve as a support for the wall A⁴, which may be termed an "upper" bridge-wall. The gases pass from the throat C into the chamber D, the uptake A⁹, the boiler-flues, and out through the smoke-stack L.

It will be seen that the construction is comparatively simple and affords means for fully

utilizing the heat while protecting those parts of the setting which are most liable to deterioration.

Having thus described my invention, I claim as new and desire to secure by Letters Patent—

A boiler-furnace, comprising a setting with a fire-chamber, a grate therein, a bridge-wall rising above the grate in the rear thereof, a transverse wall depending from the top of the setting in vertical alinement with the bridge-wall to within a distance therefrom, forming a throat therewith, a combustion-chamber located in the rear of the said throat and communicating therethrough with the fire-chamber, horizontal circulating-tubes connected with the boiler and arranged transversely upon the top surface of the bridge-wall and

upon the lower surface of the said transverse depending wall, each tube of the upper set being located in the same vertical plane with one of the tubes of the lower set, and air-supply channels located in the bridge-wall and in the transverse wall respectively and terminating in superposed transverse slots or air-discharge passages located in the opposing faces of said walls between the central circulating-tubes of each set.

In testimony whereof I have signed my name to this specification in the presence of two subscribing witnesses.

WILLIAM FORDYCE BEECHER.
